(57) CLAIM

The ornamental design for a dress as shown and described.

DESCRIPTION

FIG. 1 is a front elevation view of a first embodiment of a dress in a first configuration;

FIG. 2 is a rear elevation view of the dress of FIG. 1;

FIG. 3 is a left side view of the dress of FIG. 1;

FIG. 4 is a right side view of the dress of FIG. 1;

FIG. 5 is a top plan view of the dress of FIG. 1;

FIG. 6 is a bottom plan view of the dress of FIG. 1;

FIG. 7 is a front elevation view of the dress of FIG. 1 in a second configuration;

FIG. 8 is a rear elevation view of the dress of FIG. 7;

FIG. 9 is a left side view of the dress of FIG. 7;

FIG. 10 is a right side view of the dress of FIG. 7;

FIG. 11 is a front elevation view of a second embodiment of a dress in a first configuration;

FIG. 12 is a rear elevation view of the dress of FIG. 11;

FIG. 13 is a left side view of the dress of FIG. 11;

FIG. 14 is a right side view of the dress of FIG. 11;

FIG. 15 is a top plan view of the dress of FIG. 11;

FIG. 16 is a bottom plan view of the dress of FIG. 11;

FIG. 17 is a front elevation view of the dress of FIG. 11 in a second configuration;

FIG. 18 is a rear elevation view of the dress of FIG. 17;

FIG. 19 is a left side view of the dress of FIG. 17; and,

FIG. 20 is a right side view of the dress of FIG. 17.

The evenly broken lines (dash-dot lines) shown in the Figures are only for illustrative purposes to show visible portions of the dress and form no part of the claimed invention.

The boundary lines (as opposed to the evenly broken lines) shown in various ones of the Figures in dash-dot-dot form do not exist in reality in the respective article embodying the design and are only for illustrative purposes to show bounds of the claimed design. It is understood that the claimed design extends to the boundary but does not include the boundary.
